UNITED STATES PATENT OFFICE.

ARTHUR E. REUSS, OF CINCINNATI, OHIO, ASSIGNOR TO THE GENERAL IRON WORKS COMPANY, OF CINCINNATI, OHIO, A CORPORATION OF OHIO.

AIR HEATER.

Application filed October 3, 1927. Serial No. 223,666.

It is the object of my invention to provide a new and improved heater or furnace in which the air to be heated is forced to move in a path reverse to its natural direction of movement; further, to provide a novel arrangement of passages respectively for the products of combustion and for the air being heated; further, to provide novel forms of walls and assembling of said walls for forming crossing serpentine passages; further, to provide a novel arrangement of serpentine passages respectively for the products of combustion and for the air being heated; further to provide novel means for moistening said air; further, to provide a novel arrangement of open-ended crossing passages and deflectors for connecting the ends of neighboring passages; further, to provide novel means for sealing said deflectors; further, to provide a novel arrangement of means for assembling the passages and deflectors; and, further, to provide novel means for moving the air being heated and enhancing the flow of the products of combustion.

The invention will be further readily understood from the following description and claims, and from the drawings, in which latter:

Fig. 1 is a perspective view of my improved device.

Fig. 2 is a perspective view of one corner of the heater, showing the arrangement of passages and deflectors and means for connecting the same, partly broken away.

Fig. 3 is a sectional view of a detail, showing the blower, taken on the line 3—3 of Fig. 1.

Fig. 4 is a vertical cross-section of a portion of my improved device, taken on the line 4—4 of Fig. 1.

Fig. 5 is a vertical cross-section of the firebox and moistening means for the air being heated, taken on the line 5—5 of Fig. 1, and partly broken away.

Fig. 6 is a vertical longitudinal section of my improved device, taken in the plane of the line 6—6 of Fig. 7, and partly broken away.

Fig. 7 is a vertical cross-section of my improved device, taken in the plane of the

line 7—7 of Fig. 6, and partly broken away. 50

Fig. 8 is a horizontal section of my improved device, taken in the plane of the line 8—8 of Fig. 6.

Fig. 9 is an enlarged sectional detail, taken in the plane of the line 8—8 of Fig. 6, partly 55 broken away; and,

Fig. 10 is a horizontal section of my improved device, taken in the plane of the line 10—10 of Fig. 6.

The fuel for heating my improved heater 60 is exemplified as gas, although other fuel, either solid, liquid or gaseous, may be employed. A fire-box 11 has the fuel element therein, represented as gas burners 12, provided with air mixing openings 13, and projecting toward each other in pairs for producing combined flames, the burners being attached to a manifold 14, with which a feed-pipe 15 connects, a control-valve 16 being in the feed-pipe. 65

The body of the fire-box may be a casting, and is exemplified of rectangular form, and provided with ribs 17, and having open ends, which are respectively closed by sheets 18, 19. 70

Above the fire-box, passages 21 are shown 75 rectangular in cross-section provided with upper walls 22, lower walls 23 and side walls 24, 25. These passages are open-ended as shown at 26, 27. The walls form flat rectangular tubes made out of metal sheeting, 80 the edges of which are connected at 28, as by means of welding. The lower one of these passages, designated 29, has side walls 30, 31, which project downwardly alongside of the flanges 32, 33, extending downwardly at the 85 respective ends of the fire-box top, the lower ends of said side walls and said flanges being secured together, as by welding.

These passages are arranged one above the other in the heater, and are spaced apart by 90 spaces 41, which form passages arranged between and at right angles to the passages 21.

One of the ends of the top wall of the respective first-named passages 21 is bent away from the passage to form a flange 44 at right 95 angles to said top wall and secured to the end edge of the lower wall of the corresponding passage thereabove, as by welding, as shown

at 48. The alternate ends of said upper walls are so bent and connected to form one of the side walls of the passages 41. The opposite ends of the upper and lower walls of the passages 21 are reversely bent toward each other, to form flanges 45, (see Fig. 7), to form the other side wall of the passages 41. These passages are open-ended as shown at 46, 47.

10 Deflectors or return bends 51, 52, shown of semi-cylindrical form, connect neighboring passages, 21, 29, such neighboring passages being above one another, at the respective ends of said passages. (See Figs. 7 and 15 8.) These deflectors are shown formed in sheets 49, 50, and have connecting webs 53, 54, therebetween, which are connected with the flanges 45, as by means of welding. The upper wall of the upper one of the first-named 20 passages 21 has upwardly extending flanges 55 at its respective ends. The deflector sheet 49 has an upwardly extending flange 56. The flange 56 and the flange 55 proximate thereto are fixed together, as by means of welding.

25 An upper deflector 57 at the other end of the passages 21 forms one wall of an inlet-port 58 for said first-named passages. The opposite wall of said inlet-port is formed by a bent sheet 59, having a curvature similar 30 to the curvature of the wall 57, and is provided with a flange 60. The flange 60 and the flange 55 proximate thereto are connected together, as by means of welding. A lower deflector 61 at the same end of the lower passage 29 forms a deflecting wall into an extension 62 for said first-named passages 21. This extension forms a passage about both sides and the bottom of the fire-box. The outer walls 63, 64, 65, of said extension passage are formed by a sheet of metal which is parallel with the sides and bottom wall of the fire-box. The upper end of the wall 63 is provided with an outwardly extending flange 66 and the lower end of the lower deflector 61 is provided with a flange 67, the flanges 66, 67, being rigidly secured together, as by welding.

The lower end of the deflector sheet 49 is provided with a reverse bend to form a foot-plate 71, which rests on the top wall of the fire-box, its outer end being formed as a flange 72, which is secured to the upper end of the side wall of the fire-box, as by welding. A sheet 73 extends lengthwise of the heater, 55 its lower end 74 laps the flange 72 and being secured thereto, as by welding.

This sheet forms the inner wall of the passage extension 75 for the heated air alongside the nest of cross-passages. This passage extension forms an extension of the passage 62. The outer wall of this upper end of the passage extension is formed by a sheet 76, provided with a flange 77 at its lower end, with which a flange 78 at the upper 65 end of the outer wall 65 is complementary, the

flanges 77, 78, being secured together, as by means of welding.

The deflectors are shown curved and form connecting passages 79, 80, between the proximate open ends of neighboring passages 21. 70 The outer walls of said connecting passages are formed by said deflectors and the inner walls thereof are formed by the side walls of the cross-passages 41.

The passages 21 extend throughout the 75 major portion of the width of the furnace and, with the connecting passages, form a serpentine passage for the air to be heated. The direction of movement of the air in said passages is indicated by the arrows *a*. The air 80 is received through the inlet port 58 and is exemplified as having a downward course in said passages above the fire-box. It is forced around the bottom of the fire-box and then ascends in the ascending stretch of 85 the passage, and is delivered through the discharge port 81 of said passage.

The air to be heated is preferably forced in a direction reverse to the direction of natural flow of heated air, which would be upward in the serpentine passage. The air to be heated is forced downward, as by means of a blower 85, which comprises an electric motor 86 and a fan 87 in an intake chamber 88, to which a pipe 89 may lead from a suitable source, as from the outside air, or the air may be received through said pipe from the house or rooms or space to be heated. A hood 90 is located between the blower and the inlet port 58, and directs the air into the 100 air passage of the furnace. (See Fig. 4.)

The heated air is discharged through the outlet port 81, and enters a hood 91, which directs the heated air into a drum 92, from which suitable heating pipes, shown at 93, and provided with usual dampers 94, direct the heated air to the desired point of use, as to the various rooms in the dwelling, or to other spaces to be heated.

The products of combustion are received 110 through an opening 101 in the rear wall 19 of the fire-box or combustion chamber. The respective upper walls and lower walls of the passages 21 above the fire-box form respectively the lower wall and the upper wall 115 of the passages 41 crossingly arranged with relation to the first-named passages, the side walls of said last-named passages being formed by the bent ends of the upper and lower walls of the first-named passages 21, as hereinbefore explained. (See Figs. 6 and 7.) The ends of neighboring passages 41 above one another are connected at the respective ends of said passages by means of deflectors 102, 103, which are formed in deflector sheets 104, 105, at the respective ends 120 of said passages 41.

The said sheets are provided with connecting webs 106, connected with the side walls of the passages 21 at alternate sides of said 125

passages 21, as by welding. (See Fig. 6.) The upper end of the deflector sheet 104 is provided with an upwardly extending flange 107 connected with the side wall of the upper 5 first-named passage 21, as by welding. The lower end of said sheet is provided with a flange 108, connected with the side wall of the lower passage 21.

The upper end of the deflector sheet 105 10 is extended as a wall 109 of the outlet-port 110, which wall extends crosswise at the front end of the furnace. The opposite wall 111 of said outlet-port is formed by a sheet of metal extending crosswise of the furnace, 15 and is provided with an upwardly turned flange 112 connected with the upper side wall of the upper passage 21.

The deflectors are shown curved and form connecting passages 113, 114, between the 20 proximate open ends of neighboring passages 41. The outer walls of said connecting passages are formed by said deflectors and the inner walls thereof are formed by the side walls of the cross-passages 21. A deflector 115 forms the outer wall of a connecting passage 116, which connects with the fire-box. The inner wall of the passage 116 is formed by the side wall of the lower air 25 passage 29. The upper and lower ends of 30 said last-named deflector are respectively provided with flanges 117, 118, secured respectively to the side wall of the lower passage 21 and to the wall 19 at the lower side of the opening 101, as by means of welding.

35 A serpentine passage extending back and forth is thus provided for the products of combustion, the course of the products of combustion being indicated by the arrows *b*. The products of combustion have a serpentine course back and forth between the passages through which the air being heated moves back and forth in a serpentine path. The products of combustion are separated from the heated air by the single thickness 40 of sheet-metal which forms the dividing wall between the passages through which the products of combustion and the air respectively pass, providing for extreme transference of heat to said air.

45 The ends of the deflectors, the ends of the outlet ports, and the ends of the extension passages for the air being heated are, as thus far described, open.

The open ends of the deflectors are at the 50 respective corners of the heater or furnace arranged at right angles to each other, as exemplified in Figs. 2 and 8. Right angular corner-pieces 121 are provided at the corners at one side of the heater.

55 Each of these corner-pieces comprises a sheet 122, which form end walls for each of the deflectors 52, for the inlet-port 58, and the connecting portion 123 of the air passage above the fire-box.

The other sheet 124 of one of said corner pieces forms an end-wall for the deflectors 102 and 115. The other of these corner-pieces 121 comprises a sheet 125, which forms an end wall for the other end of each of the deflectors 103 and the outlet-port 110. These respective 60 sheets and walls are secured together, as by means of welding.

The corners in the angles of said corner pieces are connected with the superposed edges of the walls of said passages 21, 29 and 75 41, as by means of welding.

The outer edges of said corner-pieces are respectively provided with flanges 126, 127, secured to the walls 128, 129, 130, of an outer casing 131 for the heater.

80 The other ends of the deflectors 102, 115, and the opposite ends of the deflectors 51 at the other side of the heater, and the opposite ends of the upper passage 75 of the delivery portion of the heated air conduit are closed 85 by corner-pieces 132.

One of these corner-pieces is provided with a sheet 134, which is connected to the other 90 ends of the deflectors 102 and 115. The other of these corner-pieces is provided with a sheet 135, which is connected to the other ends of the deflectors 103 and the outlet-port 110, as by means of welding for closing said ends.

Said corner-pieces comprise sheets 136 across the ends of the open-ended deflectors 95 51 and across the ends of the upper delivery portion 75 of the heated air passage, being connected with said ends, as by means of welding to form a tight joint.

The corner in the angle of said corner-pieces is connected with the superposed edges of the walls of the respective passages at said corners, as by means of welding.

The outer edges of said corner-pieces are provided with flanges 137, 138. The flanges 105 137 are connected respectively with the walls 128, 130, and the flanges 138 are connected with the wall 139 of the outer casing.

The corners of said outer casing are preferably rounded, as at 140, for pleasing appearance of the heater. The casing is also provided with a top plate 141 connected with upright walls of the casing by angle irons 142, as by means of welding. The top plate may also be connected with the upper wall of the upper cross-passage 21 by means of channel plates 143, connected respectively with said wall and said top-plate by means of welding.

All of the joints between the combustion chamber, the passages for the products of combustion and the passages for the air are securely made, to prevent passage of the products of combustion into the air passages, or vice versa, and to prevent a mixture of the air to be used for heating and the products 120 of combustion.

The front wall 18 and the rear wall 19 of the fire-box, which are shown as plates, are

secured to the respective ends of said chamber, as by means of welding. These plates are shown as extending to the bottom wall 145 of the casing. The outer upright walls of the casing are connected to the bottom wall by means of angle irons 146, as by means of welding. The end walls of the fire-box and the bottom wall or plate of the casing may be connected together, as by means of angle irons 147 by means of welding. (See Fig. 6.)

The bottom wall 64 of the lower cross-passage of the air conduit below the fire-box is connected at its respective ends to the respective front and rear plates of the fire-box, as by means of brazing.

The casing may be supported on legs 149 shown as angle irons provided with feet 150, the angle irons being received through the bottom of the casing and secured to the front and rear plates 18, 19, as by means of welding.

The fire-box or combustion chamber is shown provided with an inlet opening 151, the walls of which are formed by a channel frame 152. The front wall of the casing and the front wall of the fire-box are provided with complementary openings, the margins of which are secured to the channel frame, as by means of welding. A door 153, hinged by hinges 154 to the front wall of the casing is provided for said opening. The door is provided with a regulating shutter 155.

Clean-out openings 161 are provided for the respective passages for the products of combustion. These openings are shown in the deflectors 102, 103 and 115, and are shown extended by walls 162 having inner flanges 163 fixed to the margins of said openings, as by welding, and extending outwardly so as to open at the outside of the casing. (See Figs. 6, 8 and 9.) A closure 164 is provided for each of these openings.

The respective closures comprise an inner wall 165 of a curvature corresponding to the general curvatures of the deflectors. Outwardly extending walls 166 extend from said inner wall, an outer wall 167 being received across the outer ends of said outwardly extending walls and forming a box-like structure for the closure, which is preferably securely closed to form an air-tight cavity in the closure, which serves as an insulating space. The closure is provided with a handle 168.

The closure is provided with a marginal groove 169, in which a packing 170 is received. The packing coacts with the outer end of the wall 162 of the opening, to form a fume-tight seat for said closure. The closure is arranged to be clamped in place to insure the sealing of said seat by means of jaws 171 having clamping lugs (see Fig. 9) and pivotally received about screws 172 fixed in the outer wall of the deflector, and having thumb-

nuts 173 received about their outer thread-end ends for clamping the closure in place.

The wall of the casing is throughout its inner face provided with a heat insulating lining 175, consisting for instance of asbestos heat-insulating block sheeting. The top space 70 176 above the upper air passage 21 is preferably a dead-air space, being closed around its edges by means of the channel-pieces 143 and the flanges 55.

In the present construction the products 75 of combustion are received through the cross-passages and deflectors provided therefor, which cross-passages are exemplified as rectangular in cross-section, extending back and forth throughout substantially the horizontal 80 cross-sectional area of the heater, and having the cross-passages for the air being heated, also exemplified as rectangular in cross-section, extending back and forth crossingly between the same, and extending substantially 85 throughout the horizontal cross-sectional area of the heater.

Single walls of metal are thus provided by this construction between the passages for the products of combustion and the passages for 90 the air being heated, enabling substantially all of the heat in the products of combustion to be transferred to the air being heated.

The spaces 181, 182, into which the deflectors 51, 52, for the air being heated, extend 95 are preferably dead-air spaces, being sealed all around, and the spaces 183, 184, into which the deflectors 102, 115, 103, for the products of combustion, extend are also preferably dead-air spaces, being sealed all around. No 100 heat is therefore lost to the outside of the heater. Any heat radiated by any of the lower deflectors into said respective spaces is absorbed by deflectors thereabove. The lower deflectors of the serpentine passage for the 105 products of combustion aid in reheating the products of combustion passing through deflectors thereabove for again transferring the heat thus absorbed to the air being heated.

Means are provided for moistening the air. 110 These means are exemplified as an absorbent pad 189 from which moisture may be absorbed by the air passing the same. This absorbent pad is shown located below the combustion chamber. The lower wall 64 of the 115 lower cross-passage is shown provided with perforations 190, through which moisture from the absorbent pad may be drawn into the lower cross passage 62 by the air passing through the latter. (See Figs. 5 and 7.) The 120 absorbent pad is preferably separated from the pad of heat insulating material between said lower wall and the lower wall of the casing, as by means of a frame 191 of channel-irons, surrounding the body of absorbent material, between said body and the body of heat-insulating material, and fixed to the 125 lower wall 64.

Absorbent strips 192 connect with the absorbent pad and depend therefrom, these strips being flexible. The strips and pad are of such material as to absorb water by capillary attraction. The strips may hang into a body of water in a reservoir 193, shown as a drawer sliding in guideways 194 on the bottom wall of the furnace. A plate 195 supports the absorbent pad and is provided with slots through which the strips pass. The plate and absorbent pad and strips are removable by removing the guideway 194.

A pipe 196 extends from the drawer and has a funnel 197 at its outer end. The top of the funnel is at the level of the desired height of water in the reservoir. The reservoir is arranged to be filled through the funnel. The desired height of the reservoir is indicated by the water in the funnel remaining at the height of the top of the funnel. The pipe 196 and funnel may be used as a handle for the reservoir. When the reservoir is moved in or out its rear and front walls respectively pass under the depending strips, which strips flex out of the way of said walls. When the reservoir is pushed inwardly the strips will automatically position themselves in the body of water in the reservoir.

30 The outlet-port connects with a hood 201, from which a flue 202 extends.

If it should be found, in the installation of the heater, that the heat remaining in the products of combustion passing from the heater is not sufficient to cause natural rise thereof in the flue, the outward movement of said products of combustion may be supplemented by an artificial draft obtained from the blower.

40 As an exemplification of this, the hood 90 may be provided with a pipe 203, connecting said hood 90 with the flue, the latter connection being preferably at a point above a damper 204 in said flue. (See Figs. 1 and 3.) A gate 205 is adjustable to regulate the passage of air through said pipe or to entirely close the same. The gate is connected with a handle 206 for operating the gate. The damper 204 regulates the passage of products 50 of combustion in the flue but preferably does not close the flue.

In order to take care of condensation in the products of combustion, the upper portion of the serpentine passage for the products of combustion is provided with a depression 207, which is shown in the wall 109. The condensation in the products of combustion collects in said depression and is discharged through a pipe 208 to a suitable point outside of the heater.

The sheets, angle irons, channel irons and other parts of the heater, except otherwise specified, may be made of metal, and all permanent joints may be suitably made, as by welding. The flues or passages above the

fire-box form a stack of crossing tubes which are rectangular in cross-section and rigidly connected. The ends of the side walls of the crossing passages form superposed ends at the respective corners of the stack of passages which are connected with the corner-pieces by welding, these corner-pieces also closing the ends of the deflectors.

Having thus fully described my invention, what I claim as new, and desire to secure by Letters Patent, is:

1. An air heater comprising a pair of series of crossing passages respectively for products of combustion and for air being heated, and a pair of series of deflectors at the ends of said respective series of passages, said deflectors connecting neighboring ones of said respective series of passages for forming crossing serpentine passages, said deflectors provided with connecting webs at the inner ends of said deflectors connecting superposed deflectors, and means securing said webs of the deflectors for each of said series of passages to the walls of the other of said series of passages with said deflectors extending outwardly from said walls.

2. An air heater comprising a pair of series of crossing passages respectively for products of combustion and for air being heated, and a pair of series of deflectors at the ends of said respective series of passages, said deflectors connecting neighboring ones of said respective series of passages for forming crossing serpentine passages, said deflectors provided with connecting webs at the inner ends of said deflectors connecting superposed deflectors, means securing said webs of the deflectors for each of said series of passages to the walls of the other of said series of passages with said deflectors extending outwardly from said walls, and means for forcing the air being heated through its passage in a general direction which is downward.

3. An air heater comprising a pair of series of crossing passages respectively for products of combustion and for air being heated, said crossing passages substantially rectangular in cross-section, the upper walls of one of said series of passages forming the lower walls of the other of said series of passages, and the ends of said walls of one of said series of passages bent to form the sides of the other of said series of passages, and a pair of series of curved deflectors at the ends of said respective series of passages connecting neighboring ones of said respective series of passages forming deflecting passages of substantially the same cross-sectional areas as the cross-sectional areas of said respective series of passages, superposed deflectors of said respective series of curved deflectors connected by webs integral with said deflectors, means securing said webs of said deflectors for each of said series of passages to the walls of the other of said series of passages, said series of

passages and said deflectors forming crossing serpentine passages.

4. An air heater comprising a pair of series of crossing passages, said passages comprising side walls, a pair of series of deflectors at the ends of said respective series of passages connecting neighboring ones of said respective series of passages and forming connecting passages between neighboring passages 10 of said series about the side walls of intermediate passages, forming serpentine conduits respectively for products of combustion and for air being heated, a casing outside said deflectors, a deflector of said serpentine conductor for said products of combustion provided with an opening, a wall for said opening connecting with said casing outside said deflector, and a closure for said opening in said wall, said closure provided with an inner wall which forms a substantial continuation of said deflector at said opening.

5. An air heater comprising a pair of series of passages having side walls crossingly arranged, a pair of series of deflectors at the 25 ends of said respective series of passages connecting neighboring ones of said respective series of passages forming connecting passages between said neighboring passages about the sides of intermediate passages, said 30 deflectors extending outwardly beyond said side walls and with said passages forming crossing serpentine passages respectively for the products of combustion and for the air being heated, a casing outside said deflectors, 35 and heat insulating material along the inner face of said casing, there being a dead air space between said heat insulating material and said crossing serpentine passages, said deflectors extending into said dead air space.

40 6. An air heater comprising a pair of crossing serpentine passages respectively for products of combustion and for air being heated, said serpentine passage for said products of combustion having a flue at its upper end, 45 said serpentine passage for the air being heated having an upper end, a blower communicating therewith for forcing movement of air in said last-named serpentine passage in a direction reverse to the natural flow of said 50 heated air, and a passage communicating with said blower and said flue for introducing a current of air into said flue to assist the natural flow of the products of combustion.

7. An air heater comprising a pair of crossing serpentine passages respectively for products of combustion and for air being heated, said serpentine passage for said products of combustion having a flue at its upper end, said serpentine passage for the air being heated having an upper end, a blower communicating therewith for forcing movement in said last-named serpentine passage in a direction reverse to the natural flow of the heated air, a passage communicating with 65 said blower and said flue for introducing a

current of air into said flue to assist the natural flow of the products of combustion, means for controlling the flow in said last-named passage, and a damper in said flue, and said last-named passage connecting with 70 said flue above said damper.

8. In a heating device, the combination of a plurality of flues substantially rectangular in cross-section arranged one above the other and having spaces substantially rectangular in cross-section therebetween, said flues provided with flanges at their ends and closed at their sides, the upper and lower walls of said flues forming the lower and upper walls of said spaces, said flanges of said flues bent to form side walls for said spaces which thereby form flues at substantial right angles to said first-named flues, and deflectors connecting neighboring ends of said respective flues for forming crossing serpentine passages respectively for the products of combustion and for air being heated and for directing the products of combustion and the air in alternate paths in crossing directions.

9. In a heating device, the combination of a plurality of rectangular flues arranged one above the other and having rectangular spaces therebetween, said flues provided with flanges at their respective ends and closed at their sides, the upper and lower walls of said flues forming the lower and upper walls of said spaces, said flanges of said flues bent to form side walls for said spaces to provide flues at substantial right angles to said first-named flues, and thereby forming a stack of crossing flues having closed sides alternately superposed at the four sides of said stack, and a sheet at each of said sides having outwardly bent portions forming deflectors and intermediate webs integral with said deflectors, 95 said deflectors respectively encompassing neighboring ends and intermediate closed sides, and means attaching said webs of said sheets to said closed sides for forming crossing serpentine passages respectively for the 100 products of combustion and for the air being heated.

10. An air heater comprising an inclosing casing a pair of series of crossing alternating superposed passages respectively for products of combustion and for air being heated, and a pair of series of deflectors at the ends of said respective series of passages, said deflectors connecting neighboring ones of said respective series of passages for forming crossing serpentine passages respectively for said products of combustion and for said air being heated in said casing, the upper portion of said serpentine passage for said products of combustion provided with a depression in said casing for condensation, and a pipe connecting with said depression and extending to outside said casing for draining said condensation from said depression to outside said casing.

11. An air heater comprising a pair of series of crossing serpentine passages respectively for products of combustion and for air being heated, a blower communicating with said serpentine passage for said air being heated for forcing movement of air in said last-named serpentine passage, and a passage communicating with said blower and having connection with said serpentine passage for said products of combustion for assisting the natural flow of the products of combustion through said last-named serpentine passage. In testimony whereof, I have hereunto signed my name.

ARTHUR E. REUSS.
